W. P. BRERETON

GOLF BALL

Filed March 1, 1924

FIG. 1

FIG. 2

Inventor
W. P. Brereton

BY

UNITED STATES PATENT OFFICE.

WILFRED P. BRERETON, OF WINNIPEG, MANITOBA, CANADA.

GOLF BALL.

Application filed March 1, 1924. Serial No. 696,302.

To all whom it may concern:

Be it known that I, WILFRED P. BRERETON, of the city of Winnipeg, in the Province of Manitoba, Canada, a subject of the 5 King of Great Britain, have invented certain new and useful Improvements in Golf Balls, of which the following is the specification.

The invention relates to improvements in 10 golf balls and particularly to a ball especially constructed for playing indoor golf, and an object of the invention is to provide a novel type of golf ball which will not be injurious to any interior furnishings, which 15 can be struck with considerable force and will absorb considerable of the shock and which can be given various effective spins, depending on the nature of the clubs used and which when it lands will hold to the 20 spot rather than roll.

A further and general object of the invention is to provide a ball which will permit of the game of golf being played in the usual manner within a house or such like 25 building and with absolute safety to interior furnishings, the interior furnishings being really desirable as hazards rather than a disadvantage in playing the game.

With the above more important objects in 30 view the invention consists essentially in the arrangement and construction of parts hereinafter more particularly described, reference being had to the accompanying drawing in which:

Fig. 1 is a side view of the ball.

Fig. 2 is an enlarged detailed sectional view of a portion of the ball.

In the drawing like characters of reference indicate corresponding parts in the several figures.

The ball body 1 is spherical, hollow and light and I have found that the celluloid ball, as employed in playing table tennis or ping pong, is quite suitable for my purpose.

I cover the ball body with a covering which is fairly thick and presents considerable nap as indicated at 2.

In the present instance I have shown a cloth covering 3 and this is used as a base 50 to hold comparatively short lengths of yarn which are looped or darned through the cloth or base and have their ends extending

outwardly, the ends of the yarn covering the whole exterior surface of the complete ball and being cut an equal length so that 55 the exposed face is uniformly spherical.

Whilst I have mentioned the cloth 3 as the base, yarn might be knitted to enclose the body 1 and then serve the same purpose as the cloth 3. Further comparatively thick 60 cloth having a considerable nap might be substituted to enclose the ball body and the exterior face of the cloth roughened or crushed to give the same effect as the yarn.

A ball of this kind is light and when 65 struck with the golf club, quite severely, will not travel very far for two reasons: First, on account of its lightness and second because the covering of the ball body is of such a nature that it absorbs considerable of 70 the shock. The ball, however, is sufficiently heavy to keep its course when struck and the surface of the ball being comparatively soft and having a high coefficient of friction permits the player, with the proper 75 club, to effectively spin the struck ball, the amount and nature of the spin being to all intents and purposes a replica of that produced in outdoor golf. Further when the spun ball lands, it tends to retain its position this also by virtue of the spin given the ball and the absorbent and frictional nature of the ball covering.

Obviously various clubs will be provided for playing indoor golf with my ball, the 80 clubs resembling those utilized for outdoor golf, with the exception that they are somewhat lighter and smaller and permitting of all the various shots being made when playing the indoor game as can be made on the 85 usual golf links.

What I claim as my invention is:—

A hollow, celluloid ball enclosed within a cloth covering and having short lengths of yarn darned through the covering and 90 enclosing the entire exterior surface of the covering, the ends of the various lengths of 95 yarn extending radially outwardly from the ball and being cut off to give a spherical exterior face.

Signed at Winnipeg, this 29th day of January, 1924.

WILFRED P. BRERETON,
